UNITED STATES PATENT OFFICE.

OREN C. THOMPSON, JR., OF METAMORA, MICHIGAN.

OIL OR GASOLINE CAN.

SPECIFICATION forming part of Letters Patent No. 368,983, dated August 30, 1887.

Application filed April 22, 1887. Serial No. 235,790. (No model.)

To all whom it may concern:

Be it known that I, OREN C. THOMPSON, Jr., a citizen of the United States, residing at Metamora, in the county of Lapier, State of Michigan, have invented certain new and useful Improvements in Oil or Gasoline Cans, of which the following is a specification, reference being had therein to the accompanying drawings.

- 10 This invention has relation to that class of oil or gasoline cans that are provided with pumps, and among the objects of the invention are to construct a can of this class that is cheap and safe, and the pump of which is capable of being withdrawn wholly from the can for cleansing, filling, and other purposes, and which by its construction is capable of discharging the liquid contained therein into any suitable receptacle.
- 15 Other objects and advantages of the invention will hereinafter appear, and the novel features thereof will be particularly pointed out in the claims.

Referring to the drawings, Figure 1 is a central vertical section of an oil or gasoline can constructed in accordance with my invention, and provided with my improved pump. Fig. 2 is a plan view; and Fig. 3 is a central vertical section, on an enlarged scale, of the barrel and the tubes therein.

Like letters indicate like parts in all the figures.

In carrying my invention into practice I use any can, A, of ordinary construction and provide the same with a vent, A', slot A², and a swinging pivoted gate, A³, to close said vent, and with a knob projecting through the slot for manipulating the gate. An opening, A⁴, is formed in the top or head of the can, which is provided with an inwardly-projecting screw-threaded flange or bushing, A⁵, through which the barrel B, containing the pump, is adapted to pass, the lower end of the barrel being seated in a seat, A⁶, having perforations A⁷. A cover, B', is tightly secured to the barrel B, the top of which is flared and formed with screw-threaded openings B² B³, having perforated screw-caps mounted thereon, the lower end of the cover being screw-threaded and adapted to take into the threads of the bushing A⁵, by which means the barrel

is held in place. A diaphragm, B⁸, is secured in and near the upper end of the barrel, and a diaphragm, B²⁸, is secured near and in the lower end of the barrel, and these serve to close said ends liquid and air tight and to maintain the tubes in position. An opening, B⁹, is formed in the barrel above the diaphragm B⁸ to permit any drippings of oil which may collect upon the upper surface of the diaphragm to run back into the can through the opening B⁹.

Within the barrel are the tubes C, D, and E, the first mentioned being provided with the discharge-pipe C', vertically movable therein, and having at its lower end a packing, C², whereby when not in use it may be forced down out of the way, and thereby incapable of discharging liquid received into the tube through the opening C³ thereof by reason of said packing, and the lower end of the discharge-pipe being below said opening. The tube D is provided with an upwardly-opening valve, D', communicating with the interior of the barrel, and with a pipe, D², communicating with the tube or cylinder E, which is open at its lower end and provided with an upwardly-opening valve, E'. Within the tube or cylinder E is mounted the piston E², the rod of which projects through the perforated cap B⁶ and is provided with a handle or knob for reciprocating the same.

The operation is as follows: Taking the piston in the position shown, an upstroke of the same will create a vacuum below it in the tube E, causing the valve E' to lift and permit the liquid to pass therein. The tube E being filled a downstroke of the piston closes the valve E' and forces the liquid into the cylinder D through the branch D² and up into the barrel B. By repeating this operation the barrel becomes filled, except at its upper end above, about the line X, which portion contains compressed air, which tends to produce a steady flow from the discharge-pipe while the piston E² is being reciprocated. Subsequent reciprocation of the piston forces the liquid in the barrel through the discharge-pipe C' and out into any receptacle. When the receptacle is filled the pumping operation ceases and the discharge-tube is pushed down.

Having described my invention, what I claim is—

1. The combination of the barrel B, having the diaphragms B³ and B², the pump E E' E², the tubes C D D², tube D having the valve D', and tube C having the opening C³, and a discharge-pipe telescopically mounted in the tube C, substantially as specified.

2. The combination of the barrel B, a pump arranged therein, the tube C, having the opening C³, and the discharge-pipe C', adapted to snugly fit and reciprocate within the tube C, substantially as specified.

3. The combination of the barrel B, having the screw-threaded cover B', adapted to fit the bushing of a can, and having the diaphragm

B³ and openings B³ B², the screw-threaded caps B⁴ B⁵, a pump, and a discharge-pipe, substantially as specified.

4. The combination, with the barrel B, screw-threaded cover B', caps B⁴ B⁵, tubes C D E, piston E², valves E' D', connecting-pipe D², and discharge-pipe C', substantially as specified.

In testimony whereof I affix my signature in presence of two witnesses.

OREN C. THOMPSON, JR.
